UNITED STATES PATENT OFFICE

THEODORE H. BAUCK, OF WATERBURY, CONNECTICUT, ASSIGNOR TO THE E. J. MANVILLE MACHINE COMPANY, OF WATERBURY, CONNECTICUT, A CORPORATION OF CONNECTICUT

DIE-HOLDING MEANS FOR METAL HEADING AND TRIMMING MACHINES

Application filed September 24, 1928. Serial No. 307,909.

This invention relates to the means which are employed for holding the dies in automatically operating machines designed to head, trim, punch and perform similar operations on metal blanks, and more particularly to the means which secure the die holder in the die holding block of such machines.

The object of the invention is to provide a simple and cheap means which can be easily and quickly manipulated for firmly securing the die holder in, or releasing the die holder from, the die holding block of such machines whereby the time required for the removal and substitution of dies is reduced to a minimum, and without completely detaching the securing means.

In attaining this object the die holder is fitted in a vertical dove-tail mortice in the front face of the die holding block, which mortice on one side has a fixed gib and on the other side has a gib that is hinged to the die holding block by a vertical pintle. Clamp plates, arranged on the top and bottom of and engaged with the die holding block and with the hinged gib, are adapted to be clamped by a screw so that the plates will hold the hinged gib in such a position that it will secure the die holder in the die holding block. When the clamp screw is loosened the clamping action of the plates is relieved so that the pivoted gib can be swung out and the die holder can be removed from the die holding block without detaching any of the parts which hold it.

In the accompanying drawings which illustrate one embodiment of the invention, Fig. 1 is a view looking at the front face of the die holding block with a die holder provided with a trimming die, secured in position by means of a clamped swinging gib. Fig. 2 is a top view of the same. Fig. 3 is an edge view of the die holding block with the swinging gib and the clamp plates.

The die holding block 1 is adapted to be bolted to the inner vertical wall of the front end of the frame of a heading, trimming, punching and like machine, in the common manner. In the front face of the die holding block is a vertical dove-tail mortice adapted to receive the chamfered side edges of the die holder 2. Back of this mortice is a recess

for receiving the anvil plate 3, and an opening in which a guiding sleeve 4 is usually placed.

The die holder has an opening into which is fitted the die 5 that has a socket or opening of the necessary size and shape to perform the required work, the die illustrated having a rectangular opening 6 shaped to trim the heads of bolts. The die when in operative position is backed by the anvil plate, it has a flange 7 around its rear edge to prevent its withdrawal from the die holder and it is locked against rotation by a key 8 that is fitted into slots cut in the periphery of the die and the edge of the opening in the die holder.

One side of the dove-tail mortice in the die holding block in which the chamfered edges of the die holder are fitted, is formed by a fixed gib 9 while the other side of the mortice is formed by the beveled wall 10 of the gib 11 that is hinged to the die holding block by the vertical pintle 12 which passes through the parts in such manner that the beveled edge of the gib is capable of swinging in a horizontal plane toward and from the chamfered edge on one side of the die holder.

Yoke shaped clamp plates 13 are located above and below the die holding block. The rear end of each of these plates has a lug 14 that projects into a slot in the die holding block, and the front end of each plate has a lug 15 with a chamfered face that is designed to engage the beveled wall of a recess in the end of the swinging gib. A clamp screw 16 is passed through perforations in the clamp plates and die holding block for the purpose of drawing the plates toward each other and clamping the swinging gib in holding position. Springs 17 are preferably arranged in sockets in the die holding block about the clamp screw so as to thrust between the die holding block and the clamp plates and force the plates outward when the clamp screw is loosened.

When the clamp screw is loosened the clamp plates are thrust outward by the springs so as to release the clamps from the hinged gib which may then be swung outward leaving the die holder free to be removed from the die holding block.

die holding block. This allows the quick removal of a die and the substitution of another die when desired, without completely detaching any of the holding parts. When a die has been inserted in the die holder the holder is placed in position at the front of the die holding block and the hinged gib is swung back and securely clamped by the plates when the clamp screw is tightened.

13 The invention claimed is:

1. Die holding means comprising a die holding block having a mortice in its front face, a die holder having an opening for a die located in said mortice, a gib hinged to the die holding block and engaging and retaining said die holder in place, clamps engaging the die holding block and hinged gib for fastening said gib in position to secure the die holder to the die holding block.
2. Die holding means comprising a die holding block having a vertical mortice in its front face, a die holder having an opening for a die located in said mortice, a horizontally swinging gib hinged to the die holding block and engaging and retaining said die holder in place, clamps engaging the die holding block and hinged gib for fastening said gib in position to secure the die holder in the die block.
3. Die holding means comprising a die holding block having a vertical dove-tail mortice in its front face, a die holder having chamfered edges fitting said mortice and an opening for a die, a gib hinged to the die holding block and forming one wall of said dove-tail mortice, clamps engaging the die holding block and hinged gib for fastening said gib in place.
4. Die holding means comprising a die holding block having a mortice in its front face, a die holder fitting said mortice and having an opening for a die, a gib hinged to the die holding block and forming one wall of said mortice, clamps engaging the die holding block and hinged gib for securing said gib in place, a screw for fastening said clamps, and springs for disengaging the clamps when the screw is loosened.
5. Die holding means comprising a die holding block having a mortice in its face, a die holder fitting said mortice, a gib hinged to the die holding block and forming one wall of said mortice and means engaging the die holding block and hinged gib for securing said gib in place.
6. Die holding means comprising a die holding block having a mortice in its front face, said mortice having a fixed gib on one side and a hinged gib on the other side, a die holder having an opening for a die fitted in said mortice, clamps engaging said hinged gib for fastening said gib in position to secure the die holder in said mortice.
